UNITED STATES PATENT OFFICE

2,471,646

BED TABLE

Elise R. Norwood, Fairfax, Calif.

Application September 23, 1946, Serial No. 698,797

3 Claims. (Cl. 311—95)

1

My present invention relates to an improved bed table especially adapted for use by persons lying in bed and the device of my invention is so arranged as to permit various adjustments so that the table may be used in several positions on the bed, and will also have uses as a drawing table and easel and the like on the extended legs not used on the bed but resting on the floor.

In the accompanying drawings I have illustrated one complete example of the physical embodiment of my invention according to the best mode I have thus far devised but it will be understood that various changes and alterations may be made in the exemplified structure within the scope of the appended claims.

In the drawings:

Figure 1 is a perspective view of the table of my invention showing the shelf in elevated position.

Figure 2 is a perspective view of the shelf raised upon the lowered intermediate panel, and used as a reading table.

Figure 3 is a transverse vertical sectional view of the table in extended position and used as a drawing table; and

Figure 4 is a partial front elevational view.

Referring now to the drawings wherein like characters indicate like parts I have illustrated the present preferred embodiment of my invention as comprising a base tray 2 to which are attached the tubular legs 4 having telescoping rods 6 with feet 7 through the pivoted collars 8. Drawers as 10 may be suitably supported beneath the tray, and the upper surface of the tray is fashioned with series of depressions 12. The ears 14 of the tray receive in pivotal relation the ears 16 of the intermediate panel 18 which is thus swingable to various angles relative to tray 2 up to 180°. Panel 18 is also formed with series of depressions 19, and the braces 20 of the panel engage a selected depression of the series 12 to support the panel in angular position, and these braces are secured by means of ears 22.

The ears 24 at the opposite edge of the panel are secured in pivotal relation to the flanges 26 of the shelf 28 by means of wing nuts 30. Shelf 28 can be swung to various angles relative to panel 18 up to 180°.

The flanges 26 also have secured thereto the braces 32 by means of the pins 34 for engagement selectively with the series of depressions 19, and the shelf 28 may be provided with a mirror 36 suitably mounted thereon for use in shaving or dressing the hair by a person in the bed.

Spring clamps 38 secured to the shelf will en-

2

gage a book or newspaper in reading position to relieve the person in the bed from holding the same.

The shelf has attached thereto collars 40 by pivot pins 42 and these collars are suitably secured to the tubular legs 44 having extensions 46 pivotally attached as at 48 and the telescoping rods 50 having feet 52 may be extended from the tubular legs 44 as desired.

As seen in the drawings the intermediate panel may be adjusted upon its pivotal mountings at any desired angle, and the braces will sustain the panel in selected position. The shelf being pivotally attached to the panel may be adjusted with relation thereto and supported thereon as in Figure 1, or the shelf may be fully extended and supported from the floor by its legs as in Figure 3. Other obvious arrangements may be made by various position adjustments of the panel and shelf, and when not in use, the legs may be folded and the panel and shelf closely superimposed upon the base tray to effect a compact rectangle for storage.

Having thus fully described my invention, what I claim as new and desire to secure by Letters Patent is:

1. A folding bed table comprising a base tray having pivotally mounted legs depending therefrom, an intermediate panel pivoted at one edge to the tray, the pivotal connection of the panel to the tray adapted to permit swinging of the panel to selected angles up to 180° relative to the tray, a shelf pivotally mounted to the other edge of the panel, the shelf being swingable to selected angles up to 180° relative to the tray, means for adjustably supporting the panel with relation to the tray, and the shelf with relation to the panel, and legs carried by the shelf and engageable with a supporting surface.

2. A folding bed table comprising a base tray having pivotally mounted legs depending therefrom and formed with a series of depressions along the sides thereof, an intermediate panel pivoted along one edge to one edge of the tray and angularly adjustable relative to the tray up to 180°, pivotal braces on the panel selectively engageable with a depression, a shelf pivotally mounted along one edge to the opposite edge of the panel for angular adjustment relative to the panel up to 180°, brace means on the shelf engageable with receiving means on the panel, and supporting-surface engaging legs connected to the opposite edge of the shelf.

3. A table including a base tray, legs for the tray, a panel pivoted along one edge to one edge

of the tray for swinging into positions of angular adjustment relative to the tray up to 180°, adjustable brace means extending between the panel and tray for retaining the panel and tray in selected positions of angular adjustment of less than perpendicularity, a shelf pivoted along one edge to the other edge of the panel for swinging into positions of angular adjustment relative to the panel up to 180°, adjustable brace means extending between the shelf and panel for retaining the shelf and panel in selected positions of angular adjustment of less than perpendicularity, and legs connected to the other edge of the shelf and engageable with a supporting surface for retaining the panel and tray, and the panel and shelf respectively, in adjusted angular relationships from perpendicularity up to 180°.

ELISE R. NORWOOD.
